UNITED STATES PATENT OFFICE.

ARTHUR L. MOORE, OF CLEVELAND, OHIO.

DESIGN FOR A CRANK-HANGER FOR BICYCLE-FRAMES.

SPECIFICATION forming part of Design No. 28,353, dated March 8, 1898.

Application filed October 9, 1897. Serial No. 654,723. Term of patent 14 years.

To all whom it may concern:

Be it known that I, ARTHUR L. MOORE, a citizen of the United States, residing at Cleveland, in the county of Cuyahoga and State of Ohio, have invented and produced a new and original Design for Crank-Hangers for Bicycle-Frames, of which the following is a specification, reference being had to the accompanying drawings.

10 Figure 1 is an end view of a crank-hanger for a bicycle-frame, showing my new design. Fig. 2 is a plan view thereof.

As shown in the drawings, the leading or material features of my design consist of a tubular cylindrical body A and four seamless tubular cylindrical lugs B, C, D, and D', each having a convex arch-shaped extremity. The lug B projects from the body at a point midway between its ends and extends upward and slightly forward. The lug C projects

from said body midway between its ends and extends therefrom upward and slightly rearward. The two lugs D and D' project from said body near opposite ends thereof and in a rearward direction. The two lugs B and C ²⁵ are of substantially the same diameter, which diameter is greater than the diameter of the lugs D and D'.

Having described my invention, what I claim as new, and desire to secure by Letters Patent, is—

A design for a crank-hanger for bicycle-frames as herein shown and described.

In testimony whereof I affix my signature in presence of two witnesses.

ARTHUR L. MOORE.
